UNITED STATES PATENT OFFICE.

FOSKETT BROWN, OF NASHVILLE, TENNESSEE.

AUTOMATIC FLUSHING DEVICE.

Application filed October 23, 1926. Serial No. 143,598.

This invention relates to automatic flushing devices and has for its object a device of this character having no moving parts, except a float control valve for regulating the flow of water to the flushing tank.

According to this invention the device comprises a flushing tank, a siphon for supplying water from the flushing tank to the bowl to be flushed, an air lock for normally rendering the siphon inoperative, an air lock release normally sealed by water and means for removing the water from the air lock release to permit the siphon to become operative. The means for removing the water from the air lock release is controlled by the depth of waste water in the discharge pipe from the bowl. The discharge pipe from the bowl leads into a compression chamber from which a pipe or tube leads to the air lock release. Accumulation of water in the chamber compresses the air in the tube with the result that the sealing water is forced out of the air lock release thereby permitting the siphon to become operative and causing water to flow from the flushing tank to the bowl. A second siphon leads from the compression chamber and is so arranged that it becomes operative to drain out the compression chamber after a predetermined head has been reached in the discharge pipe.

During the flushing operation the level of the water in the flushing tank is lowered sufficiently to break the siphon and the air lock release is again sealed with water. The breaking of the siphon stops the flow of flushing water and the tank is refilled up to a level determined by the float valve, the air lock being reestablished.

The flushing operation is controlled by the level of the waste water in the discharge pipe from the bowl and the flushing operation takes place automatically. There are no moving parts connected with the flushing control mechanism, the release of the flushing water being accomplished by the establishment of a siphon through the release of air normally preventing siphoning.

Other objects, novel features, and advan-

tages of this invention will be apparent from the following specification and accompanying drawing, wherein the single figure is a vertical section through an apparatus embodying the invention.

In the drawing, 1 represents a bowl to be flushed and 2 is a pipe by means of which water is supplied from the flushing tank 3 to the bowl 1. From the bottom of the bowl 1 a discharge pipe 4 leads to a compression chamber 5, the discharge pipe 4 terminating at a distance above the bottom of the tank 5. A siphon 6 leads from the tank 5 at a point lower than the end of the discharge pipe 4.

In the flushing tank 3 is arranged an air lock which comprises an inverted cup shaped member 7 having an inner cylindrical partition 8 of greater length than the outer wall of the member 7. Between the outer wall of the member 7 and the partition 8 is arranged a cylindrical member 9 extending from the bottom of the tank 3. Within the partition 8 is provided a tubular member 10 extending from the bottom of the tank 3 above the upper edge of the member 9 and communicating with a spout 11 projecting into a chamber 12 directly beneath the flushing tank 3. A tube 13 is arranged between the partition 8 and the member 9 and terminates at a point above the upper edge of the member 10 and extends through the bottom of the tank 3 to a point near the bottom of the chamber 12 where it assumes a horizontal position. From the top of the compression chamber 5 a tube 14 rises to a height approximating the top of the member 10 and then is returned through an aperture in the wall of the chamber 12 to connect with the horizontal portion of the tube 13. From the horizontal portion of the tube 13 extends a riser 15 in position to receive water from the spout 11. A valve 16 operated by the float 17 controls the flow of water to flushing tank 3.

The drawing shows the device ready for operation. The end of the siphon 6 in the chamber 5 is sealed by residual liquid from the preceding flushing. Air is trapped in

the air lock 7 and the air lock release tube 13 is sealed with water from the preceding flushing operation, the riser 15 being filled and the level in the vertical portion of the tube 13 being dependent upon the compression of the air in the air lock 7. The operation is as follows: Waste water is introduced into the bowl 1 and discharged through the pipe 4 into the compression chamber 5. As the waste liquid accumulates in the compression chamber it forces air through the tube 14 thereby displacing the sealing water in the tube 12 and riser 15. When the head in the compression chamber and discharge pipe exceeds the head in the air lock release tube all the water is forced out through the riser 15 thereby permitting the flow of air through the air lock release tube 13 to the atmosphere. Because of the head of water in the flushing tank 3, the water in the air lock displaces the air through the tube 13 until the water flows over the edge of the member 10 thereby forming a siphon. The water flowing through the siphon refills the riser 15 and flows on through the pipe 2 flushing the bowl 1 and completely filling the compression chamber 5. When the level of the water in the discharge tube 4 has exceeded the height of the bend in the siphon 6 the latter becomes operative and drains out the chamber 5. The flow of water through the siphon in the flushing tank 3 lowers the level of the water in the tank until it drops below the outer edge of the air lock thereby permitting air to flow in and break the siphon. In the meantime the valve 16 has been opened by operation of the float 17 so that water flows therethrough into the tank. As the air lock release tube 15 has been refilled with water, air cannot escape from the air lock and there can be no further flow through the siphon 10. The tank 3 therefore fills up until the valve 16 is closed by the float 17. The breaking of the siphon 6 is accomplished when the level of the water in the compression chamber 5 drops below the end of the siphon 6. There will, however, be sufficient residual liquid to seal the end of the siphon to make it ready for the next flushing operation.

It will thus be seen that the automatic flushing is accomplished without the use of any moving parts, thereby rendering the operation very simple and preventing its getting out of order. Furthermore, the device is of simple construction and easy of manufacture.

What I claim as new and desire to secure by Letters Patent of the United States is:

1. An automatic flushing device, comprising a bowl, a discharge line therefor including a trap, a flushing tank, a siphon for delivering fluid from said tank for flushing the bowl, an air lock normally sealed with fluid and rendering said siphon inoperative

and means for automatically releasing the air lock when the liquid in the discharge line reaches a predetermined level.

2. An automatic flushing device comprising a bowl, a discharge line therefor including a trap, a flushing tank, a siphon for delivering liquid from said flushing tank to flush said bowl, an air lock sealed with fluid and rendering said siphon inoperative, an air lock release normally sealed with liquid and means for removing the liquid from the air lock release when the liquid in the discharge line reaches a predetermined level.

3. An automatic flushing device comprising a bowl, a discharge line therefor including a trap, a flushing tank, a siphon for delivering liquid from said flushing tank to flush said bowl, an air lock sealed with fluid and rendering said siphon inoperative, an air lock release normally sealed with liquid and comprising a U-tube having one end positioned to receive liquid discharged through the siphon and means for removing the liquid from the U-tube when the liquid in the discharge line reaches a predetermined level.

4. An automatic flushing device comprising a bowl, a discharge line therefor including a trap, a flushing tank, a siphon for delivering liquid from said flushing tank to flush said bowl, an air lock sealed with fluid and rendering said siphon inoperative, an air lock release normally sealed with liquid comprising a U-tube having one end positioned to receive liquid discharge through the siphon, an air tube leading from a low point of the discharge line to the bottom of said U-tube whereby liquid in the U-tube is forced out when the liquid in the discharge line reaches a predetermined level.

5. An automatic flushing device comprising a bowl, a discharge line therefor including a trap, a flushing tank, a siphon for delivering liquid from said flushing tank to flush said bowl, an air lock sealed with fluid and rendering said siphon inoperative, an air lock release normally sealed with liquid, and an air tube leading from a low point in the discharge line to the air lock release, whereby change of level of liquid in the discharge line compresses the air in the air tube to force out the sealing liquid from the air lock release.

6. An automatic flushing device comprising a bowl, a discharge pipe leading to a compression chamber, a siphon for draining said compression chamber, said siphon being normally sealed with residual liquid in said chamber, a flushing tank, a siphon for delivering liquid from said tank for flushing the bowl, an air lock sealed with fluid and rendering the flushing siphon inoperative and means responsive to the level of the liquid in said chamber for releasing said air lock.

7. An automatic flushing device comprising

ing a bowl, a discharge pipe leading to a compression chamber, a siphon for draining said compression chamber, said siphon being normally sealed with residual liquid in 5 said chamber, a flushing tank, a siphon for delivering liquid from said tank for flushing the bowl, an air lock sealed with fluid and rendering the flushing siphon inoperative, an air lock release normally sealed with 10 liquid and means for removing the liquid from the air lock release when the liquid in the chamber reaches a predetermined level.

8. An automatic flushing device comprising a bowl, a discharge pipe leading to a 15 compression chamber, a siphon for draining said compression chamber, said siphon being normally sealed with residual liquid in said chamber, a flushing tank, a siphon for delivering liquid from said tank for flushing 20 the bowl, an air lock sealed with fluid and rendering the flushing siphon inoperative, an air lock release normally sealed with liquid and comprising a U-tube having one end positioned to receive water discharged 25 through the flushing siphon and an air tube leading from the top of the compression chamber to the bottom of said U-tube.

9. An automatic flushing device comprising a bowl, a discharge pipe leading therefrom to a compression chamber, a siphon for 30 draining said compression chamber and normally sealed by residual liquid, a flushing tank, a discharge pipe therein for delivering liquid to flush said bowl, an inverted cup 35 shaped member having an inner cylindrical partition surrounding said discharge pipe, a cylindrical member rising from the bottom of the tank and terminating between the outer wall of said cup shaped member and 40 said partition, a U-tube having one end projecting into said cup shaped member between the partition and said cylindrical member and the other end arranged below said discharge pipe and an air tube leading 45 from said compression chamber to the bottom of said U-tube.

10. An automatic flushing device comprising a bowl, a discharge pipe leading therefrom to a compression chamber, a siphon 50 for draining said compression chamber and normally sealed by residual liquid, a flushing tank, a discharge pipe therein for delivering liquid to flush said bowl, an inverted cup shaped member having an inner cylindrical partition surrounding said discharge pipe, a cylindrical member rising from the bottom of the tank and terminating between the outer wall of said cup shaped member and said partition, a U-tube having one end 55 projecting into said cup shaped member between the partition and said cylindrical member and the other end arranged below said discharge pipe, an air tube leading from said compression chamber to the bottom of 60 said U-tube, and a pipe for supplying liquid 65

to said tank and a float controlled valve for regulating the flow of fluid to said tank.

11. In combination, a liquid container having an outlet provided with an air trap subject to the head of liquid in said container, a liquid supply passage having an air trap and discharging into said container, a pipe leading from one of said traps to the other and having a liquid seal subject to the pressure in said outlet air trap and provided with a vent, whereby the air trap in said passage is vented upon rise of liquid in said container. 70 75

12. In combination, a liquid container having an outlet provided with an air trap 80 subject to the head of liquid in said container, a liquid supply passage having an air trap and discharging into said container, a pipe leading from one of said traps to the other and having a liquid seal subject to the pressure in said outlet air trap adapted to receive liquid from said supply, whereby the air trap of said passage is vented upon rise of liquid in said container and said seal is filled by liquid from said supply. 85 90

13. In combination, a liquid container having an outlet provided with an air trap subject to the head of liquid in said container, a liquid supply passage having an air trap normally sealed with liquid and discharging into said container, and means 95 operated by compression of the air in said outlet air trap for venting the air trap of said liquid supply passage.

14. In combination, a liquid container having an outlet provided with an air trap, a liquid supply passage having an air trap normally sealed with liquid and discharging into said container, and means utilizing the air trapped in said outlet air trap for unlocking the air trap of said supply passage. 100 105

15. In a device of the character described, a container having an outlet provided with an air chamber, a liquid conducting passage having an air chamber and discharging into 110 said container and a pipe having a liquid seal provided with a vent and directly communicating at its ends respectively with said air chambers and being otherwise closed.

16. In a device of the character described, a container having an outlet provided with an air chamber, a liquid conducting passage having an air chamber and discharging into 115 said container, and a pipe having a liquid seal provided with a vent and directly communicating at its ends respectively with said air chambers and being otherwise closed, the vent opening of said vent being in the path of liquid discharged from said supply. 120

17. An automatic flushing device comprising a bowl, a discharge line therefor including an air trap, a flushing tank, a line for delivering liquid from said tank to said bowl, said line including a siphon and an air lock normally sealed with liquid for rendering 125 130

said siphon inoperative, and means for automatically releasing said air lock in response to pressure changes in said air trap.

18. An automatic flushing device comprising a bowl, a discharge line therefor including an air trap, a flushing tank, a line for delivering fluid from said tank to said bowl, an air lock in said line normally sealed with

liquid for preventing flow from said tank to said bowl, and means for automatically releasing said air lock when the liquid in the discharge line reaches a predetermined level.

In testimony whereof, I have signed my name to this specification.

FOSKETT BROWN.
